UNITED STATES PATENT OFFICE.

ETIENNE WITZBERGER, OF CARNEGIE, PENNSYLVANIA, ASSIGNOR TO WITZBERGER HEATING APPLIANCES COMPANY, A CORPORATION OF PENNSYLVANIA.

COLLAPSIBLE HEATING-STOVE.

1,394,390.

Specification of Letters Patent.

Patented Oct. 18, 1921.

Application filed February 25, 1921. Serial No. 447,683.

To all whom it may concern:

Be it known that I, ETIENNE WITZBERGER, a citizen of the United States, residing at Glendale, Carnegie, in the county of Allegheny and State of Pennsylvania, have invented new and useful Improvements in Collapsible Heating-Stoves, of which the following is a specification.

This invention relates to heating stoves, and more particularly to a stove which can be readily collapsed or folded for shipping.

One of the main objects of the invention is to provide a stove of the character stated of simple construction and light weight which may be readily collapsed so as to occupy a minimum of space for shipping, and which may be readily set up. A further object is to provide a stove which is effectively locked against collapsing or folding when set up. Another object is to provide a stove composed of a minimum number of parts so constructed and related as to facilitate quick assembling of the stove. Further objects will appear from the detailed description.

In the drawings:

Figure 1 is a front view of the stove in set up condition.

Fig. 2 is a central vertical sectional view of the stove in set up condition taken from front to back.

Fig. 3 is a section taken substantially on line 3—3 of Fig. 1.

Fig. 4 is an enlarged detail fragmentary section taken substantially on line 4—4 of Fig. 1.

Fig. 5 is an enlarged fragmentary detail section taken substantially on line 5—5 of Fig. 1.

Fig. 6 is a horizontal section taken substantially in the plane of line 6—6 of Fig. 2.

Fig. 7 is a plan view of the stove in folded condition as assembled for shipment.

Fig. 8 is a section taken through the stove in folded condition substantially on line 8—8 of Fig. 7.

Fig. 9 is a fragmentary detail section of the means for securing the top on the stove.

The body of the stove is formed of end plates 1 and 2 and a back plate 3 and upper and lower front plates 4 and 5, all of these plates being formed of sheet metal of suitable gage. At their adjacent edges the plates are provided with interfitting inwardly projecting sleeves 6 which receive pintle wires

7 which project below the plates and have their lower portions turned outwardly to provide spring elements 7^a. Wire 7 passes through an opening in a web member 8 which extends across a foot member 9 of substantially rectangular cross-section. This foot member is provided at its upper end with integral rectangularly disposed flanges or arms 10 which fit snugly about the corners of the stove when set up so as to lock plates 1, 2, 3 and 5 in extended relation and effectually prevent collapsing or folding of the body of the stove. When the foot member is applied web member 8 is inserted over spring element 7^a the lower end of which engages into the angle of the foot member, after which the foot member is pressed inwardly slightly toward the body of the stove so as to place spring element 7^a under tension, the foot member being then slid upwardly into operative position, in which position it will be effectively held by the action of spring element 7^a which serves to press the flanges or arms 10 snugly about the lower corners of the body of the stove so as to secure the plates in extended condition as previously stated.

A front opening 11 is left between the front plates 4 and 5, and a lower corrugated reflector plate 12 is provided at its lower forward edge with sleeves 13 which interengage with sleeves 14 formed at the upper edge of lower front plate 5. A pintle wire 15 is inserted through the sleeves 13 and 14 so as to hingedly secure the reflector to plate 5. This reflector, when in operative position, fits snugly between end reflector plates 16 which are secured at their ends about the pintle wires 7, these end reflector plates being positioned on the inner faces of the end plates 1 and 2 of the body of the stove.

An upper reflector plate 17 is hinged at its lower edge at 18 to the inner face of back plate 3 and is provided adjacent to its upper edge with a stop strip 19 pivoted to the plate at 20 and of such length as to contact with the upper front plate 4 when extended so as to support the reflector plate 17 at an inclination forwardly and upwardly of the stove. This leaves an opening 21 for escape of the products of combustion which flow into the space 22 in the upper end of the stove. Back plate 3 is provided with an escape opening 23 com-

municating with space 22 and with a collar 24 surrounding this opening for attachment of a pipe which may be connected to a flue in any suitable or preferred manner.

5 Top 25 is formed of sheet metal of suitable gage and is provided with an arcuate depending peripheral flange 26 adapted to fit snugly about the end and front and back plates of the stove body. Each of the plates 10 of the body is provided at its upper end with outwardly turned flange 27 adapted to snap into flange 26 of top 25 when the top is forced over the upper ends of the plates. This serves to secure the top upon 15 the stove so as to prevent accidental displacement of the same, and the top serves to effectually lock the plates forming the body of the stove in extended relation and to effectively prevent collapsing or folding 20 of the stove body. The top 25 is reinforced by corner plates 28 secured thereto by bolts, rivets, or in any other suitable or preferred manner. These corner plates have depending arcuate flanges 29 which fit snugly about 25 flange 26 of the top so as to effectively reinforce the same and prevent spreading apart of flange 26 when the top is applied.

The end plates 1 and 2 are provided with 30 openings 30 which are alined transversely of the stove when the stove is set up. These openings are adapted to receive a burner 31 of a known type so as to support the burner above and adjacent to the upper portion of reflector plate 12. This burner is 35 provided at one end with a depending nipple 32 adapted to receive a hose for connecting the stove to a suitable source of supply of gas, and with a control valve 33. A bracket 34 projects from nipple 32 and fits snugly 40 against the outer face of end plate 2. This bracket receives a stove bolt 35 which passes through the end plate and is provided on its inner end with a nut 36. This provides means for quickly and easily securing the 45 burner 31 to the stove and insures that the burner will be properly positioned relative to upper reflector 17.

By removing top 25 and foot members 9 and burner 31, the body of the stove and the 50 reflectors carried thereby may be readily collapsed so as to occupy a minimum of space. To collapse or fold the body of the stove, reflector 12 is turned upwardly to fit snugly against the inner face of upper front 55 plate 4, covering the opening 11 as in Fig. 7, it being understood that reflector 12 has sufficient flexibility to be readily moved into substantial parallelism with the front plate of the stove body. After this has been done, 60 member 19 is turned so as to be positioned within the outline of reflector 17, this reflector being then turned upwardly so as to fit snugly against the inner face of back plate 3. With the reflectors in the positions 65 stated, the body of the stove may be readily

collapsed or folded in the manner illustrated in Fig. 8, after which the top together with the burner and foot members may be placed upon the body, the whole stove when thus collapsed occupying but very little space. 70 As will be understood, the body of the stove and the top and burner and foot members may be placed in a carton for shipment in any preferred manner, the manner of packing illustrated in Fig. 7 being only one of 75 many which can be employed. A stove constructed in the manner illustrated and described may be readily produced at small cost and can be quickly and easily set up or collapsed when desired. It is possible to 80 ship twelve of these stoves in collapsed condition in the space required to ship a stove of similar dimensions in set up or uncollapsed condition. This effects a material saving in the space required for shipment 85 which is frequently a very important consideration. As will be understood, it may be found desirable in practice to resort to changes in details of construction and arrangement of parts of the invention, and I 90 intend to include all such variations, as fall within the scope of the appended claims, in this application in which the preferred form only of my invention is disclosed.

What I claim is:—

1. In a stove of the character described, a body consisting of hinged foldable front and back and end plates, foot members provided with elements arranged and adapted to engage about the corner portions of the 100 body when the body is set up, said foot members acting to hold the plates substantially at right angles to each other, and means for detachably securing the foot members to said body. 105

2. In a stove of the character described, a body consisting of hinged, foldable front and back and end plates, foot members provided with elements adapted to engage about the corner portions of the body when the plates 110 are disposed at right angles to each other, and means for hingedly connecting the plates together and for securing said foot members to the body. 115

3. In a stove of the character described, a body including front and back and end plates, said plates being provided at their adjacent edges with interfitting sleeves, pintle wires inserted through said sleeves and projecting below the body, foot members provided at their upper ends with arms disposed at right angles to each other and adapted to fit about the corner portions of the body when extended so as to hold said plates at right angles to each other, and means for detachably securing said foot members on the lower portions of the wires. 120

4. In a stove of the character described, a body consisting of front and back and end plates provided at their adjacent edges with 130

interfitting sleeves, pintle wires inserted through said sleeves and projecting below the body, foot members provided at their upper ends with rectangularly disposed arms adapted to fit snugly about the lower corners of the body when extended, and means for detachably securing the foot members upon the lower portions of said pintle wires and for forcing said arms 10 toward the body.

5. In a stove of the character described, a body including front and back and end plates provided at their adjacent edges with interfitting sleeves, pintle wires inserted 15 through said sleeves and projecting below the body, the lower end portion of each of said wires being curved outwardly of the body, foot members of substantially rectangular cross-section provided at their upper 20 ends with rectangularly disposed arms adapted for snug engagement about the lower corners of the body when extended, and means for detachably securing said foot members on the lower portions of the wires, 25 the outwardly turned lower end portions of said wires bearing against the inner faces of the foot members so as to press the arms at the upper ends thereof snugly about the corners of the body.

30 6. In a stove of the character described, hingedly connected back and end plates, an upper and a lower front plate hinged at their ends to the forward ends of said end plates, a lower reflector hinged at its lower 35 end to the upper edge of said lower front plate, an upper reflector hingedly secured at its lower edge to the inner face of said back plate remote from the upper end thereof, means for supporting the upper reflector at 40 an upward and forward inclination when the stove is extended and with its upper edge spaced away from said upper front

plate, and means for securing the plates substantially at right angles to each other.

7. In a stove of the character described, 45 front and back and end plates hingedly connected at their adjacent edges, a lower reflector hinged at its lower edge to said front plate adjacent to the lower end thereof, an upper reflector hinged at its lower edge to 50 the inner face of the back plate remote from the upper end thereof, foot members adapted to engage about the corner portions of adjacent plates when the stove is extended so as to retain the plates substantially at 55 right angles to each other, means for detachably securing the foot members to said plates, and a cover member adapted to engage over the upper ends of the plates when extended and to secure them substantially 60 at right angles to each other.

8. In a stove of the character described, a collapsible body consisting of hingedly and permanently connected front and back and side plates, legs adapted to fit about the 65 corners of the body when extended and to hold said plates substantially at right angles to each other, and means for detachably securing said legs to the body and for forcing the legs toward said body.

9. In a stove of the character described, 70 a collapsible body consisting of hingedly and permanently connected side and back plates, and upper and lower front plates, a lower reflector hingedly secured at its lower 75 edge to the upper edge of said lower front plate, an upper reflector hinged to the inner face of said back plate, both of said reflectors being adapted to be positioned within the body when collapsed, and means 80 for holding said body extended.

In testimony whereof I affix my signature.

ETIENNE WITZBERGER.
